CHESS PIECE

Donald E. Folley, Fayetteville, N. Y.
Application April 26, 1954, Serial No. 30,176

Term of patent 3½ years
(Cl. D34—5)

F/G. 4

F/G. 3

F/G. 2

F/G. 1

F/G. 5

Figure 1 is a side elevational view of the right side of a chess piece embodying my new design;

Figure 2 is a front elevational view thereof;

Figure 3 is a side elevational view of the left side thereof;

Figure 4 is a back elevational view thereof; and

Figure 5 is a top plan view thereof.

I claim:

The ornamental design for a chess piece, as shown.
